VICTOR E. SCHMIEDEKNECHT, OF CHICAGO, ILLINOIS.

CARBURETER.

1,135,211.

Specification of Letters Patent. Patented Apr. 13, 1915.

Application filed February 7, 1914. Serial No. 817,095.

To all whom it may concern:

Be it known that I, VICTOR E. SCHMIEDEKNECHT, a citizen of the United States, residing at the city of Chicago, county of Cook, and State of Illinois, have invented a certain new and useful Improvement in Carbureters, of which the following is a specification.

This invention relates to carbureters and has for an object to provide a carbureter that will be economical in construction and efficient in operation.

Another object is to provide a carbureter in which the degree of opening of the throttle valve may be increased without increasing the angular movement of the throttle lever.

A further object is to provide means whereby the degree of opening of the air and throttle valves may be adjusted independently of the throttle lever and without varying the maximum angular movement of said lever.

With the foregoing, and other objects in view which will appear as the nature of the invention is better understood, the invention consists in certain novel features of construction as hereinafter described and claimed, and illustrated in the accompanying drawing which forms a part of this specification, in which is set forth an embodiment of this invention, but it is to be understood that changes variations and modifications may be resorted to that come within the scope of the claims appended hereunto.

In the drawings in which like reference characters indicate like parts in the several views; Figure 1, is a central vertical section, some parts being in elevation; Fig. 2, is a section on line X-X of Fig. 1, some parts being in plan; Fig. 3, is a bottom view of the carbureter.

Referring to the drawing —1— indicates the body of the carbureter, comprising a cylindrical structure that may be assembled in any suitable manner; —2— a fuel chamber, defined by external and internal walls —3— and —4—. Within the fuel chamber is a float —5—, that may be of any suitable construction, which through the medium of a lever —6— and a valve —7— regulates the admission of fuel through an inlet —8—, and serves to maintain the fuel at a constant level within the chamber 2, after the manner well known in the art. Concentric with the

float chamber is an inner double Venturi tube —11— having two distinct contractions —12— and —13—. Said contractions may be integral projections from the wall 4, or a separate tube may be inserted. The properties of the Venturi tube are thought to be well known and to require no extended description, suffice it to say that the same volume of air will pass through the constriction as through the main portion of the passage, but at an increased speed. A bridge —9— secured in any suitable manner, to the bottom of the fuel chamber, supports a plurality of concentrically arranged tubes concentrically within the Venturi tube 11. A longitudinal fuel passage —19— through the bridge 9 is in communication with the fuel chamber 2, and has openings into the interior of the tube 14 and into an annular space —18— between the tubes 15, 16 and 17, to supply fuel thereto. Strainers —20— are disposed over the entrances to passage 19. An annular passage —17— is open at its lower end to the atmosphere, as is the passage 11. The upper end of the tube 14 is closed by a plug —21—, through which is an orifice —22— controlled by a needle valve —23—. The upper ends of the tubes 15 and 16 are covered by a cap —24—, a projection —25— from which extends into the passage 17 converting the tube 15 into a Venturi tube, and serving to divert the current of air over the orifice 22. A plurality of radial ducts —26—, in the cap 24, permits the egress of fuel from the passage 18 into the air drawn through the passage 11 by the suction of the engine. The nested tubes 14, 15, 16 with their alternate fuel and air passages form a multiple concentric jet arrangement which terminates just below the center of the lower contraction 13. The body 1 is surmounted by a domed chamber —30— provided with an outlet —31— from which a connection may be run to the engine. Secured in the dome of said chamber and depending therefrom is a tube —32— which depends nearly to the cap 24. The valve stem 23 extends upward through the tube 32 to the exterior of the chamber 30 and is provided with a thumb nut —33— by means of which it may be adjusted. A sleeve —34— is adapted to slide on the tube 32, and has secured in tandem thereon two puppet type valves —35—36—. The valve 35 being adapted to seat on the upper sur-

face of the contraction 12, and the valve 36 to seat partly on the upper surface of the lower contraction 13 and partly on the cap 24. The upper valve 35 is the main throttle valve, which varies the supply to the engine, and the lower valve is the air throttle which controls the flow of air through the passage 11. On the upper end of the sleeve 34 is a disk 37 that has depending triangular projections 38 that bear on a transverse lever, of the second class, 39 having an opening through which the sleeve 34 passes. One end, 39' of the lever is supported by an arc shaped ledge 40 which extends inward from the wall of the chamber, the other end 39'' rests on a cam 41. The cam 41 is secured on a shaft 42 which extends exteriorly of the chamber and is provided with a lever 43, by means 20 of which the cam is actuated. The cam is mounted transversely of the chamber in a plane below the lever 39, and at right angles to the mean position thereof. The cam is practically a frustum of a cone and so secured on the shaft that one surface lies in a plane parallel therewith; by this arrangement the lift of the cam varies from a minimum at one end to a maximum at the other. A vertical shaft 44 journaled in a bearing 50 in the wall of the chamber is provided on its outer end with a lever, or handle 45, and on its interior end with a crank 46 having a wrist 47 which enters an elongated slot 48 in the lever 39. By moving the handle 45 the lever 39 may be shifted, about the sleeve 34 as a center, to bring the end 39'' to any desired position intermediate the length of the cam, the end 39' moving at the same time along 30 the ledge 40. It is to be observed that moving the lever 43 through an angle of prescribed limits, correspondingly moves the cam 41, and by reason of the end 39'' of the lever 39 resting thereon raises or lowers the lever 39 and through medium of the disk 37 imparts vertical movement to the sleeve 34, thus raising or lowering the valves 35, 36, a spring 49 holding the valves seated. By shifting the lever 39 so that the end 39'' may be 40 engaged by different points along the lift 53, of the cam 41 the opening of the valves may be varied with a fixed maximum movement of the throttle lever.

It will be observed that the amount of 55 opening of the throttle and air valves will depend on the position of the lever 39 on the cam. Further that with the cam in its inoperative position with the horizontal side presented up, the lever 39 may be shifted 60 without affecting the valves, the degree to which the valve will be opened by operation of the cam, is predetermined by the position of the lever thereon, as the height of the lift 53 which engages the lever varies, 65 but if the cam is in an operated position,

that is with the lift in a raised position, any movement of the lever therealong will vary the opening of the valves.

It is thought, that from the foregoing description, the manifold advantages of this invention has been clearly set forth and that those versed in the art pertaining thereto will readily understand the operation thereof, and be able to make and use the same and

75 I claim;

1. In a carbureter, a fuel chamber, a double Venturi tube concentric therein, valves seated on the contractions of said tube, means for operating said valves and means 80 operable to predetermine the amount said valves may be opened, or for varying the opening after the valves are opened.

2. In a carbureter, a fuel chamber, a double Venturi tube concentric within said chamber, a fuel jet centrally positioned within said tube, a concentric multiple jet spaced from said central jet, said jets having air passages surrounding them, a valve controlling said passages, means for operating said valve and means for predetermining 90 the amount said valve may be opened.

3. A carbureter having a vertical passage, valves seated in said passage, means for operating said valves, and means operable either previous to said first named means to predetermine the amount said valves may be opened or to vary the opening thereof after the operation of said first named means.

4. In a carbureter, a fuel chamber having a centrally positioned vertical passage therethrough open at its lower end to the atmosphere, a plurality of contractions within said passage, a bridge secured to the lower end of the chamber and having a longitudinal fuel passage connected with the interior of the chamber, a plurality of concentric tubes supported within said vertical passage by said bridge, certain of said tubes communicating with said fuel passage.

5. In a carbureter, a fuel chamber having a centrally positioned vertical passage therethrough open at its lower end to the atmosphere, a plurality of contractions within said passage, valves seated on said contractions, and means for operating said valves.

6. In a carbureter, a fuel chamber, a double Venturi tube centrally positioned within said chamber and open at its lower end to the atmosphere, a bridge, a plurality of concentric tubes supported within said Venturi tube by said bridge, said bridge having a fuel passage in connection with said chamber and with certain of said tubes.

7. In a carbureter, a fuel chamber, a double Venturi tube arranged centrally within said chamber, a bridge secured below said chamber, a plurality of concentric tubes supported by said bridge, said bridge hav-

- ing a fuel passage in communication with said chamber and with certain of said concentric tubes, another of said tubes and the Venturi tube being open at the lower ends 5 thereof to the atmosphere.
8. In a carbureter, a fuel chamber having a centrally positioned vertical passage therethrough open at its lower end to the atmosphere, a plurality of contractions within said 10 passage, valves seated on said contractions and means for operating said valves simultaneously.
9. In a carbureter, a fuel chamber having a centrally positioned vertical passage therethrough open at its lower end to the atmosphere, 15 a plurality of contractions within said passage, valves seated on said contractions, means for opening said valves and other means for varying the opening of said 20 valves.
10. In a carbureter, a fuel chamber, a mixing chamber above said fuel chamber, a double Venturi-tube extending centrally through the fuel chamber into the mixing 25 chamber, a bridge, a multiple concentric jet supported by said bridge within said Venturi-tube, a lever in said mixing chamber, a valve-stem depending from the center of 30 said lever, a fulcrum for said lever, a cam on which the power end of the lever rests and valves secured in tandem on said stem, 35 said valves seating on the contractions of said Venturi-tube.
11. In a carbureter, a fuel chamber, a mixing 40 chamber, a double Venturi-tube extending through said fuel chamber and opening into said mixing chamber, a bridge secured beneath said fuel chamber, a plurality of concentric tubes supported by said bridge within and terminating just short of the 45 first contraction in said Venturi-tube, said bridge having a fuel passage therethrough communicating with said fuel chamber and certain of said concentric tubes, the lower end of another of said tubes and of the Venturi-tube being open to the atmosphere, a 50 needle-valve controlling the outlet of fuel from the central of said tubes, a puppet valve controlling the flow of air through the space between the outer of said tubes and the Venturi-tube; a main valve and means 55 for operating said valves.
12. In a carbureter, a fuel chamber, a mixing chamber, a tube through said fuel 60 chamber open at its lower end to the atmosphere, valves seated in said tube, means for operating said valves comprising a lever of the second class positioned in said mixing chamber, a fulcrum for said lever, a stem depending from said lever said valves secured on said stem and a cam for raising said lever.
13. In a carbureter, a fuel chamber, a mixing chamber, a tube open at its lower end 65 to the atmosphere passing through said fuel
- chamber into said mixing chamber, valve seats in said tube, a lever in said mixing chamber, a stem depending from said lever, valves on said stem, a fulcrum for said lever, a cam with a fixed maximum angle of movement and a lift of varying height and means for shifting said lever along said cam. 70
14. In a carbureter, a lever of the second class, a fulcrum for said lever, a stem depending from said lever, valves on said stem, 75 seats for said valves, a cam for lifting said lever, said cam having a fixed maximum angle of movement, the lift of said cam increasing from one end to the other, and means for shifting the end of said lever 80 along the length of said cam.
15. In a carbureter, a lever of the second class, a fulcrum for said lever, a stem depending from said lever, valves on said stem, 85 seats for said valves, a fulcrum for the lever, a cam having a fixed maximum angle of movement, the lift of said cam increasing in the length thereof, and means for shifting the lever, with the stem as a center, along the length of said cam and 90 along the fulcrum.
16. In a carbureter, a lever of the second class having a central perforation, a valve stem resting on said lever and depending through said perforation, a valve on said 95 stem, a seat for said valve, a fulcrum, a cam the lift of which increases progressively in the length thereof, and means for shifting said lever with said stem as a center so that the power end may rest in different positions along said cam thus varying the lift of said valve. 100
17. In a carbureter, a lever of the second class having a central perforation and an elongated aperture near the fulcrum end 105 thereof, a valve stem supported by said lever and depending through said perforation, a fulcrum, a cam, a crank-shaft engaged in said aperture and adapted to shift the contact point of said lever with the cam and 110 fulcrum, a valve on said stem and a seat for said valve.
18. In a carbureter, a lever, a valve stem depending centrally from said lever, a fulcrum, an elongated cam the lift of which 115 increases through its length, a crank-shaft engaged with said lever and adapted to shift same with said stem as a center, a valve on said stem and a seat for said valve.
19. In a carbureter, a fuel chamber, a mixing chamber, a double Venturi-tube extending centrally through said fuel chamber into said mixing chamber, a bridge secured beneath said fuel chamber, a plurality of concentric tubes supported by said bridge and 120 extending within said Venturi-tube and stopping just short of the first contraction therein, said bridge having a fuel passage therethrough communicating with said fuel chamber and with certain of said tubes, the 125 130

lower end of another of said tubes and of the Venturi-tube being open at the lower end to the atmosphere, a needle-valve controlling the outlet of fuel from the central 5 of said tubes, a valve seating on the upper face of the lower contraction controlling the flow of air through the Venturi tube, a throttle valve seating on the upper contraction in the Venturi-tube, a lever having a 10 central perforation and an elongated aper-

ture, a valve stem depending through said perforation, said valves secured to said stem, an elongated cam, a fulcrum, a crank-shaft engaged in said aperture and adapted to shift said lever.

VICTOR E. SCHMIEDEKNECHT.
